[57] CLAIM

The ornamental design of an assembly tool for remote manipulation of locking container pins, as shown.

DESCRIPTION

FIG. 1 is a plan view from the side of an assembling tool showing my new design;

FIG. 2 is a perspective view of the top thereof; and FIG. 3 is a perspective view of the bottom thereof. The tool is used for remote manipulation of a locking pin to be inserted into or removed from a corner casting on a container.
